M. M. CRANE

BOOKMARK

Filed Sept. 29, 1924

INVENTOR

Mary Margaret M. Crane

UNITED STATES PATENT OFFICE.

MARGARET M. CRANE, OF LOS ANGELES, CALIFORNIA.

DESIGN FOR A BOOKMARK.

Application filed September 29, 1924. Serial No. 10,919. Term of patent 3½ years.

To all whom it may concern:

Be it known that I, MARGARET M. CRANE, a citizen of the United States, residing at Los Angeles, in the county of Los Angeles and State of California, have invented a new, original, and ornamental Design for a Bookmark, of which the following is a specification, reference being had to the accompanying drawing, forming part thereof.

The figure is a plan view of a bookmark, showing my new design.

I claim:

The ornamental design for a bookmark, as shown.

MARGARET M. CRANE.
